(57) **CLAIM**

We claim the ornamental design for a wand handle, as shown and described.

DESCRIPTION

FIG. 1 is a perspective view of a wand handle showing my new design;

FIG. 2 is a right side view thereof, the left side being a mirror image;

FIG. 3 is a front view thereof;

FIG. 4 is a rear view thereof;

FIG. 5 is a bottom view thereof; and,

FIG. 6 is a top view thereof.
